UNITED STATES PATENT OFFICE

128,297

DESIGN FOR A MUSICAL BRACELET

Catherine L. Healy, Attleboro, Mass.

Application February 19, 1941, Serial No. 99,094

Term of patent 3½ years

To all whom it may concern:

Be it known, that I, Catherine L. Healy, a citizen of the United States of America, residing at Attleboro, county of Bristol, State of Massachusetts, have invented a new, original, and ornamental Design for a Musical Bracelet, of which the following is a specification, reference being had to the accompanying drawing, forming a part thereof.

Fig. 1 is a side view of a musical bracelet showing my design; and

Fig. 2 is an edge elevational view thereof.

I claim:

The ornamental design for a musical bracelet, substantially as shown.

CATHERINE L. HEALY.
